UNITED STATES PATENT OFFICE.

ARTHUR ST. CLAIRE STOCKS, OF LONDON, ENGLAND.

POWDER-PUFF AND POWDER-CONTAINER.

1,095,171.

Specification of Letters Patent. Patented Apr. 28, 1914.

Application filed April 24, 1913. Serial No. 763,433.

To all whom it may concern:

Be it known that I, ARTHUR ST. CLAIRE STOCKS, a subject of the King of Great Britain and Ireland, residing at 48 Bread street, London, E. C., England, have invented a Powder-Puff and Powder-Container, of which the following is a specification.

This invention relates to a powder puff and powder container for toilet use, and has for its object to provide a powder puff and a receptacle for powder in a neat and attractive form and for complete inclosure when not in use within a casing of small dimensions. This object is accomplished according to the invention by providing a puff such as usually employed for toilet use with a flexible shield or base and securing the puff to a slide capable of movement within an open ended casing, in such manner that upon the slide being drawn into the casing the puff is completely inclosed and compressed within the shield and is at the same time drawn into the casing.

The invention is illustrated in the accompanying drawings in which,—

Figure 1 is a sectional elevation of a puff and powder container provided according to the invention. Fig. 2 is an elevation of the casing with the cap removed and with the puff in its position for use. Fig. 3 is a view of the end face of the cap.

In carrying the invention into effect as illustrated in the accompanying drawings I provide a casing *a* advantageously of cylindrical form closed at one end, and open at the other. I provide a cylindrical member *b* adapted to slide within the said casing and I cause the movement of the cylindrical member *b* within the casing by mounting pins *c* upon it in diametrically opposite positions to slide within longitudinal slots *d* provided in corresponding position in the casing *a*. I

secure the puff *e* to a flexible shield *f* made of silk or other suitable material having its edges extending advantageously beyond the 45 puff so as completely to inclose it on its being drawn into the casing, and I provide means for securing the puff and the puff shield to the end of the cylindrical member *b*. For this purpose loops *b*¹ may be cut out 50 of the metal at the end of the cylindrical member. It will thus be understood that by movement from the position indicated in Fig. 2 to the position indicated in Fig. 1 the puff *e* is compressed and is drawn into the 55 casing.

The cap *g* is formed for reception within the open end of the casing *a* and is provided as a powder container. For this purpose an open ended cylindrical part *h* closely fits 60 into the cap *g* and at its lower end a number of holes *i* are provided. A button *j* serves to carry a valve plate *k* by means of which the holes *i* may be closed. The valve plate *k* may be provided to have a restricted movement in any suitable manner. 65

What I claim as my invention and desire to secure by Letters Patent is:—

An article for toilet use consisting of a puff, a slide to which said puff is attached, 70 an open ended casing in which said slide is adapted to be withdrawn for inclosure of the puff when out of use and a flexible shield mounted beneath said puff and adapted to be contracted for the compression of the 75 puff on the withdrawal of the puff within the casing.

In testimony whereof I have hereunto signed my name to this specification in the presence of two subscribing witnesses.

ARTHUR ST. CLAIRE STOCKS.
